LINER HANGER

Beverly H. Scott, Maywood, Calif., assignor to
Lane-Wells Company, Los Angeles, Calif., a cor-
poration of Delaware

Application December 29, 1941, Serial No. 424,805

6 Claims. (Cl. 166—1)

My invention relates to liner hangers; that is, to devices adapted to suspend from a well casing a perforated screen or liner which continues from the well casing into the uncased producing zone below. Among the objects of my invention are:

First, to provide a liner hanger which incorporates a swivel connection whereby the liner and liner hanger may be rotated relative to each other to permit manipulation of the liner hanger in order to set or secure the liner hanger in position in the casing, even though the liner may be stuck or "frozen";

Second, to provide a liner hanger which is particularly designed to permit washing or cleaning of the well by circulation of a washing fluid around the liner, all before the liner hanger is set; and

Third, to provide a liner hanger which is particularly compact, comprises few parts and is economically manufactured.

With the above and other objects in view, as may appear hereinafter, reference is directed to the accompanying drawing, in which:

Figure 1 is an elevational view of my liner hanger shown attached to a liner;

Figure 2 is a partial elevational, partial longitudinal sectional view taken substantially through 2—2 of Figure 1, showing the parts of the liner hanger in the positions assumed when the liner hanger is in engagement with a surrounding well casing; and

Figure 3 is a transverse sectional view through 3—3 of Figure 1.

The liner hanger is provided at its upper end with an adaptor fitting 1 having, preferably, left-hand threads for separable attachment to a tubing string (not shown). The lower end of the adaptor fitting 1 is screw-threaded to a swivel shell 2. A tubular mandrel 3 telescopes into the lower end of the swivel shell 2 and is provided with an external swivel flange 4 at its upper end, which is adapted to ride upon an internal swivel flange 5 provided within the shell 2.

The swivel shell 2 is screw-threaded to a sleeve 6 which extends downwardly over the mandrel 3 and is provided at its lower end with a downwardly converging cone member 7, which may be integral with the sleeve 6 or suitably attached thereto. The cone is adapted to coact with slips 8. These slips are wedge-shaped in cross section and provided with wickers or teeth. The slips 8 are mounted at the upper ends of reins 9 in the form of straps which extend downwardly and

are secured to a lower collar 10 journaled around the mandrel 3.

Also secured to the lower collar 10 are several friction springs 11 in the form of leaf springs which extend upwardly between the slips 8 and are secured at their upper ends to an upper collar 12. The upper collar 12 is provided with one or more keeper hooks 14 which coact with pins 15 provided in the sleeve 6.

10 The lower end of the mandrel 3 is joined to a liner A and the slips when moved upwardly on the cone 7 are adapted to engage a surrounding well casing B, indicated fragmentarily in Figure 2, and shown in transverse section in Figure 3.

Operation of my liner hanger is as follows: The liner hanger is attached to the liner and to a tubing string (not shown). The liner, liner hanger and tubing string are lowered into a well bore with the parts of the liner hanger occupying the positions shown in Figure 1. When the desired level is reached the tubing string is rotated in a direction to unlatch the keeper hooks 14 from the pins 15. The friction springs 11, by 20 reason of their engagement with the surrounding casing, hold the collars and slips against rotation. After the keeper hooks and pins are free, weight is applied to the liner, which forces the cone between the slips so as to expand 25 the slips against the casing as shown in Figure 2. By reason of the swivel connection between the mandrel and shell the liner hanger may be latched or unlatched, and set or released, without requiring rotation of the mandrel or liner. Furthermore, sufficient axial clearance is provided 30 between the upper end of the mandrel 3 and the adaptor fitting 1 to permit the necessary downward movement of the cone in order to set the slips. Thus, even though the liner hanger is 35 frozen to the extent that it cannot be moved longitudinally or rotated, the liner hanger may be manipulated as desired to set or release.

Various changes and alternate arrangements may be made within the scope of the appended 40 claims, in which it is my intention to claim all novelty inherent in the invention.

I claim:

1. A liner hanger comprising: a swivel joint, one part thereof connected with a tubing string 50 and the other part suspending a liner; a sleeve connected to said one part and extending downwardly over said other part; a slip expander carried by said sleeve; and slips for coaction with said slip expander.
2. A liner hanger comprising: a swivel joint,

one part thereof connected with a tubing string and the other part suspending a liner; a sleeve connected to said one part and extending downwardly over said other part; a friction cage engageable with a surrounding casing journaled on said sleeve and extending downwardly therefrom over said slip expander; and slips carried between the extremities of said cage and adapted to coact with said slip expander.

3. A liner hanger comprising: a swivel joint one part thereof connected with a tubing string and the other part suspending a liner; a sleeve connected to said one part and extending downwardly over said other part; a friction cage engageable with a surrounding casing journaled on said sleeve and extending downwardly therefrom over said slip expander; slips carried between the extremities of said cage and adapted to coact with said slip expander; and latch means incorporating said cage and sleeve for releasably holding said cage in a position to restrain coaction between said slips and said slip expander.

4. A liner hanger comprising: means adapted to be suspended from a tubing string; a slip expander on the lower extremity of said means; a mandrel telescoping within said means and adapted to suspend a liner; a slideable and rotatable connection between said mandrel and means; slips adapted to coact with said slip expander; and a latching device including an ele-

ment carried by said means above said slip expander for restraining said slips, and a coacting element connected with said slips and said first-mentioned element.

5. A liner hanger comprising: means adaptable to be suspended from a tubing string; a slip expander on the lower extremity of said means; a mandrel telescoping within said means; a slideable and rotatable connection between said mandrel and means; slips adapted to coact with said slip expander; a friction cage extending over said slip expander and journaled on said means above said slip expander and said mandrel below said slip expander; and slips carried by said cage intermediate its ends for coaction with said slip expander.

6. A liner hanger comprising: means adaptable to be suspended from a tubing string; a slip expander on the lower extremity of said means; a mandrel telescoping within said means; a slideable and rotatable connection between said mandrel and means; slips adapted to coact with said slip expander; a friction cage extending over said slip expander and journaled on said means above said slip expander and said mandrel below said slip expander; slips carried by said cage intermediate its ends for coaction with said slip expander; and a latching device including elements on said cage and said means for restraining said slips.

BEVERLY H. SCOTT.
